ENGINES OPERATING COAXIAL SHAFTS

James B. Breckhurst, Red Bank, N. J.

Application August 2, 1943, Serial No. 496,984

10 Claims. (Cl. 123—197)

1

This invention, which comprises a development of the improvement disclosed in my application Serial No. 473,605, filed January 26, 1943, is directed to a prime mover having co-axial driven shafts which derive motion therefrom and are capable of rotation at relatively different speeds.

The co-axial shafts, due to their respective speeds of rotation, may be utilized for a variety of purposes, both mechanical and electrical, and my present development is therefore not limited to any one particular instance of power application, but rather to means whereby a single prime source of power is enabled to cause the rotation, at different speeds, of respective co-axial power shafts.

The example of my invention represented in this application is based upon a compound internal combustion engine as developed from the disclosure given in my said application Serial No. 473,605, and it embodies a cylinder having a piston whose piston rod in the reciprocating action of the piston serves to rotate the crank shaft and hence to rotate the outer one of the co-axial shafts, the said piston also being given a rotating movement that, through the connecting rod and a system of gears, imparts rotation to the inner one of the co-axial shafts, the R. P. M. of said inner shaft being supplemented by the speed of the outer shaft, when the shafts are rotated in the same direction, but the speed of said inner shaft being relatively less when said shafts are caused to rotate in opposite directions.

Whilst in my said earlier application Serial No. 473,605 the expansive power, applied through the rotation of the piston, is intended to supplement the power exerted upon the crank shaft in the reciprocating action of the piston, the present improvement is directed to the utilization of the expansive power developed through the piston rotation for the operation of a shaft that is ensheathed by and is co-axial with the usual crank shaft. Said ensheathed shaft may be designated herein as the "inner shaft" in contradistinction to the usual crank shaft, which latter may be styled the "outer shaft."

Said inner shaft, which may continue into or comprise a propeller shaft, when the engine is employed in the operation of aircraft, is capable of rotation either in the same direction as that of the outer shaft, or in the opposite direction, according to the direction of inclination of the piston flutes; also, the R. P. M. of said inner shaft is governed by the degree of angularity of said flutes—it being notable however that the rate of speed of said inner shaft, when driven in the

2

same direction as the outer shaft, is supplemented by the rotative speed of said outer shaft.

Other features and advantages of my invention will hereinafter appear.

5 In the drawing:

Figure 1 is a front sectional view of a cylinder with its piston and connecting rod as part of a nine cylinder, air cooled engine.

Fig. 2 is a side sectional view of the same, and
10 Fig. 3 is a cross section of the piston showing its peripheral flutes.

Fig. 3A is a cross section of a modified piston having reversed flutes.

In said figures let 1 indicate a cylinder forming
15 part of a nine cylinder, air cooled engine, only parts of certain remaining cylinders being illustrated in Fig. 1.

The piston for said cylinder is indicated at 2, it
20 having a lower skirt portion that is provided with
piston rings 3, said skirt portion being continued
upwardly in bell-like formation 4, with an upper
cylindrical portion 5 that carries the piston head
6, and from said piston head 6 there depends an
outer concentric wall 7 which is in movable oppo-
25 sition to the inner wall of the cylinder. Said wall
7 is provided in its outer surface with a series of
inclined flutes or vanes 8, for a purpose to be re-
ferred to hereinafter. An annular gap 9 sepa-
30 rates the piston skirt from wall 7, said gap so dis-
posed as to register with a fuel inlet 10 formed
through the cylinder wall when the piston has
compressed a charge of air in the cylinder to the
35 point where liquid fuel, injected as from a nozzle
11 through said inlet, will cause ignition and
power expansion of the charge.

It will be noted that a chamber 12 is formed be-
35 tween the piston portions 4, 5, 6 and 7, and that
the entry of the air occurs through the single in-
take and exhaust valve 13, during the down
40 stroke.

The piston cylindrical portion 5 is shown as
45 threaded interiorly and receives a screw plug 14,
that carries a universal joint 15 from which de-
pends the connecting rod 16. It should be pre-
mised now that the piston is capable of both re-
ciprocating and rotary movements, also the piston
50 rod. The piston rod, at its lower end, is revolvably
mounted in a bearing member 17 that itself is
revolvble on the crank-pin 18, also the lower end
of the piston rod is provided with a bevel gear 19
which is in mesh with a bevel gear 20 carried by
55 a shaft 21 that is journalled in bearing member
17, said shaft 21 carrying a pinion 22 which is
revolvble on crank-pin 18 and is in mesh engage-
gagement with a gear 23 loosely mounted on

crank-pin 18, and in mesh engagement with a gear 24 carried by a shaft 25 (the inner shaft) which is ensheathed by and rotatable within the crank shaft 26 (the outer shaft).

In the example illustrated the crank shaft is shown as in splined engagement with the crank-pin, though obviously it may be an integral part thereof. The two-part arrangement is suggested for production purposes.

The opposite crank arm 27 carries a crank shaft 28, and operable therein is an inner shaft 29, whose gear 30 is in mesh with a gear 31 that, like 23 is similarly operated through the rotation of piston 2.

My improved engine is intended for use in a variety of automotive applications wherein a plurality of shafts, actuated by a single piston, are adapted to perform separate and distinct functions in the same power plant assemblage. Thus, in an airplane the inner and outer shafts may operate respective co-axial propellers. Also, one of the shafts may operate a supercharger.

For automotive road vehicles respective shafts may operate right and left drive wheels and function with the aid of suitable differential gearing.

As will be apparent, the direction of rotation of the piston is governed by the direction of angle given the flutes 8 in the piston periphery, so that the inner shaft may be caused to rotate either in the same direction as the outer shaft, or oppositely.

Variations within the spirit and scope of my invention are equally comprehended by the foregoing disclosure.

I claim:

1. In an engine, the method of transmitting the power of a prime mover to co-axial telescoped shafts and causing said shafts to rotate independently in the same direction and means whereby the R. P. M. of the inner shaft is supplemented by the R. P. M. of the outer shaft.

2. In an engine, the method of transmitting the power of a prime mover to co-axial telescoped shafts and causing said shafts to rotate independently of each other whereby the R. P. M. of the inner shaft is varied by the R. P. M. of the outer shaft.

3. In an engine, the method of transmitting the power of a prime mover through a plurality of co-ordinated systems of operation having co-axial telescoped shafts rotating independently and in concert in the same direction and means whereby the R. P. M. of an inner shaft is supplemented by the R. P. M. of an outer shaft.

4. In an engine, the method of transmitting the power of a prime mover through a plurality of co-ordinated systems of operation having co-axial, telescoped shafts rotating independently of each other whereby the R. P. M. of an inner shaft is varied by the R. P. M. of an outer shaft.

5. In an engine, a cylinder, a piston, a crank shaft and a second shaft revoluble within said crank shaft, means whereby expansive power operates directly to both project and rotate said piston, means whereby the projecting movement of said piston serves to operate said crank shaft, and means whereby the rotating movement of said piston serves to operate said second shaft.

6. In an engine, the method of transmitting the power of a single prime mover directly to telescoped shafts, and causing said shafts to rotate independently and in concert.

7. In an engine, a cylinder, a hollow piston of fixed cubical capacity therein, a crank shaft and a second shaft revoluble within said crank shaft, means whereby expansive power, developed from within said piston operates directly to both project and rotate said piston, means whereby the projecting movement of said piston serves to operate said crank shaft, and means whereby the rotating movement of said piston serves to operate said second shaft.

8. In an engine having an inner and an outer driving shaft rotated independently through independent movements of the engine pistons, means for rotating the inner shaft through rotating movements of the pistons and means for rotating the outer shaft through reciprocating movements of said pistons, whereby the said inner and outer shafts are rotated in concert to affect the R. P. M. of said inner shaft.

9. In an engine having a plurality of independently rotated telescoped shafts, means for rotating the inner shaft independently of the outer shaft and means for rotating the outer shaft independently of the inner shaft, whereby the said shafts rotate in concert to affect the R. P. M. of the inner shaft.

10. In an engine having a plurality of independently rotated telescoped shafts, means for rotating the inner shaft at an established rate of speed and means for rotating the outer shaft at an established rate of speed, whereby the said shafts rotate in concert to affect the established rate of speed of the inner shaft.

JAMES B. BROCKHURST.
